AUTOMATIC BOILER CONTROL SYSTEM

Herbert Ziebolz, James D. McCracken, and Daniel T. Gundersen, Chicago, Ill., assignors to Askania Regulator Company, Chicago, Ill., a corporation of Illinois

Application June 12, 1942, Serial No. 446,750

3 Claims. (CL. 60—54)

This invention relates to an automatic boiler control system of the type employing a master regulator responsive to the boiler load or steam pressure in the header and a hydraulic coupling controlled thereby to supply the combustion supporting air to support combustion of the fuel in the boiler furnace. One of the main objects of the invention is to provide automatic control means for a hydraulic coupling employing servomotors having cross connected cylinders for controlling the valves in the lines or pipes connected to the coupling, the idea being to prevent the valves from being operated simultaneously and to avoid the usual dead spot in such a control. Furthermore, the idea is to provide a system of this type in which the control valves will close and remain closed so that the coupling can be operated by an ordinary hand control in case of oil failure. Another object is to provide control means for the coupling which is not subjected to undue friction and increasing the possibility of a dead spot in the control valves. Still another object is to provide improved control means for such hydraulic couplings adapting them for general use. A further important object of the invention is to so interconnect the valve control means for the hydraulic coupling that the valves will be operated in a specific manner and also to provide a bubbling device as a level indicator of hydraulic fluid which acts as a generator of control impulses for the operation of the valve control means.

Other aims and advantages of the invention will appear in the specification, when considered in connection with the accompanying drawing, in which:

The figure is a diagrammatic illustration of an automatic control mechanism and system embodying the invention applied to a steam boiler.

Referring particularly to the drawing, the control mechanism is shown as being connected to control the supply of combustion supporting air in proportion to the fuel requirements in a steam boiler furnace 10. The boiler 11 is shown as having an ordinary steam main or header 12 to which is connected a bellows type pressure operated diaphragm 13 acting on a pivoted lever 14 carrying the usual weight 15 which is a function of the boiler pressure. The pivoted lever 14 acts on an ordinary jet pipe regulator or relay 16 in opposition to a spring 17, the compression of which is controlled or regulated by the cam 18 connected to be actuated by a piston 19 in a cylinder 20, the latter communicating with the jet pipe relay 16 through pipes 21 and 22. The

5 piston 19 is connected to operate a second cam 23 which acts on a second jet pipe relay 24 through a spring 25 in opposition to a diaphragm 26 which, in turn, is subjected to a pressure proportional to the level of oil in the oil sump 27 of a hydraulic coupling later to be described.

10 The diaphragm 26 is shown as being arranged in a casing 28 to which is connected a pipe 29 having its opposite end 30 extending to a point near the bottom of the sump 27 and submerged in the oil therein. To this pipe is connected an air conduit 31 through which is introduced air at a suitable bubbling rate by means of a throttle valve 32a and a pressure reducing valve 32. The air will bubble out of pipe end 30 and maintain the pressure in pipe 29 proportional to the submerged depth of pipe end 30, so that when the oil level in the sump remains constant, the air pressure acting on the diaphragm 26 will likewise remain constant. If the oil level falls in the sump, the air will bubble up through it more readily from the end or opening 30 and thereby reduce the pressure of the air in the line 29 and in the casing 28. The valve 32a is adjusted to bleed air into line 29 at a rate just sufficient to keep active bubbling at the pipe end 30.

15 The jet pipe 24 forms a part of the coupling regulator and is shown as controlling two servomotors or valve control means in the form of cylinders 33 and 34 carrying spring urged pistons 35 and 36 respectively. The fluid pipes 37 and 38 leading from the jet pipe relay 24 are shown as being cross connected to the cylinders 33 and 34, the pipe 37 being connected to the outer end of cylinder 34 and also to the inner end of cylinder 33 by means of branches 39 and 40 respectively; while the pipe 38 is connected to the outer end of cylinder 33 and to the inner end of cylinder 34 by means of branches 41 and 42 respectively. Piston rods 43 and 44 extend through the outer ends of the cylinders 33 and 34 respectively, each cylinder having an unpacked bearing seal or baffle around the piston rod. The oil which leaks past the bearing seals, is drained through drain pipes 45 and 46 at the outer ends of the cylinders. The piston rods 43 and 44 are connected through pivoted levers 47 and 48, respectively, to operate control valves 49 and 50 in the drain and supply pipes 51 and 52 connected to the hydraulic coupling 53. The pump P is connected in the usual manner to supply oil through an oil pipe 54 from the sump 27 to the coupling 53 through the pipe 52 and a cooler 55 is shown as being connected between the supply and drain pipes 52 and 51.

The arrangement of the control means for the valves 49 and 50 is such that only one valve is operated at any time and the other has to wait until said one valve is closed to be actuated. For normal variations in the condition under regulation, the pistons 35 and 36 will actually wait upon each other to return by spring action to their normal positions. For example, if piston 35 is displaced from normal and piston 36 is required to move, the piston 36 will have to wait upon piston 35 to return to its normal position before it can move. This surprising operation is due to the orifice action of the two orifices in the jet pipe relay 24. When one piston is moving, oil flows into one orifice and out the other through pipes 37 and 38. There is a positive drop in the pressure in the line where oil flows in and a rise or negative drop in pressure in the line through which the oil flows out. If the pistons are held fixed and the jet of the relay 24 is moved a certain distance to the left, the pressure in the branches 39 and 40 will increase; while the pressure in branches 41 and 42 will be somewhat less, say about 55# and 45#, respectively. If the jet is displaced in the opposite direction or to the right of the center, the pressure in the branches 41 and 42 will increase and the pressure will decrease in branches 39 and 40. If, with the jet pipe displaced to the left and pressures of, say 55# and 45# respectively present in the branches 39—40 and 41—42 respectively, the pistons are released, the piston 36 will move and the piston 35 will remain stationary. Oil would then be flowing into pipe 37 and out of pipe 38. Then the pressure in the pipe 37, due to the oil flow, will drop to, say 52# and the pressure in pipe 38 will rise slightly to, say 48#. Now, if the jet pipe of relay 24 is displaced the same distance to the right of center, piston 36 will reverse its movement and hasten back to its normal or valve closing position. Oil will then flow rapidly through the branch 41 and pipe 38 and keep the pressure in the branches 38 and 40 actually less than 50# and the pressure in 41 and 42 will be more than 50#, thus preventing the piston 35 from moving. As soon as the piston 36 stops moving, the pressures immediately change to about, say 55# and 45# in the conduits 38 and 37 respectively and as soon as movement begins, it will almost immediately change to about 52# and 48# respectively, due to the flow of oil caused by the positive and negative drops across the orifices in the jet pipe relay 24. In this way, one valve waits to start until the other has returned to normal waiting position.

It will be understood that the hydraulic coupling 53 is driven by an ordinary motor M and is connected to operate the fan 56 at variable speeds depending upon the air requirements for the boiler furnace and controlled by the amount of oil fed to the coupling. The fan 56 delivers air to the boiler furnace through a conduit 57. In this instance, fluid fuel is delivered to the furnace through a conduit 58 and its supply is controlled by an ordinary jet pipe regulator 59 connected to be operated by differential furnace pressure through the usual diaphragm 60 counteracted by a diaphragm 61 operated responsive to differential pressure across a restriction in the fuel line 58. The regulator, as usual, operates a servo-motor 62 to control a fuel or throttle valve 63 in the fuel line 58.

It is believed that the operation of the system will be obvious from the foregoing description

and the drawing. The bubbling device 30 measures the oil level in the sump 27 and this level determines the oil level in the coupling 53. In most instances, the level in the coupling is inversely proportional to that in the sump. The bubbling device 30 has a further function in that it acts as a generator of control impulses for the diaphragm 26 which acts on the jet pipe relay 24 to actuate the valves 49 and 50 through the servo-motors or valve control means 35 and 36. Thus, the pressure maintained in the line is proportional to the depth of the submerged end 30 and is a function of the oil level in the coupling. The system according to the invention has many advantages and particularly the differential operation of the piston motors 35 and 36 eliminates the necessity of any packing and with the drain lines 45 and 46 the motors are practically friction free. The springs in the motors 20 are just sufficient to keep the valves closed against the valve reaction from the regulated flow and friction of the valve, whereby in case of oil failure, the valves close and remain closed so that manual control can take over without complete loss of control, which might result if either valve should thereby open wide and stay open. Since the piston areas are equal, any change in head pressure, or inlet pressure, or recovery pressure affects equal areas and is 25 therefore cancelled as far as the control is concerned. The drain lines 45 and 46 and elimination of the packing removes practically all lag or drag and results in a practically friction free motor.

The cross connections 39 and 41 result in the operation of the pistons or servo-motors 35 and 36 in such a way that they will actually wait upon each other to return to normal position; that is if one is returning to normal position, the other will not move until the first one reaches normal. In other words, if piston 35 is displaced from normal and piston 36 is required to move, piston 36 will wait for piston 35 to return to normal before starting to move. This, as has been explained, is due to the orifice action of the two orifices in the relay 24, since when a piston 35 or 36 is moving, oil is flowing in its respective orifice and out of the other orifice. There is a positive drop in the pressure in the line when the oil flows in and a negative drop or rise in pressure in the line when the oil flows out of the orifice. In this way, one valve waits to start until the other has returned to normal waiting position.

With the cross connections for the valve control means the oil level in the coupling is maintained constantly at the proper control point but upon failure of the oil pressure for the relay the coupling is maintained at the last controlled point which facilitates taking over for manual control. The control system according to the invention utilizes the full sensitivity of the control and reduces the "dead" or "insensitive" spot in a control to a minimum to thereby improve the stability of the control and eliminate "hunting."

It is of course obvious that all features shown and described need not be used conjointly. Also, the invention is not limited to the exact embodiment shown and it is not indispensable that all the features of the invention be used conjointly, 65 since they may be employed advantageously in various combinations and sub-combinations.

We claim as our invention:

1. In an automatic control system of the class described including a hydraulic coupling and embodying a pair of valve controlled conduits for

the coupling fluid and a regulator for the coupling including a jet pipe relay responsive to a controlled condition affected by the coupling, a device for operating the valves in said conduits comprising a pair of double-acting servo-motors operatively connected to the separate control valves for the coupling, each motor consisting of a cylinder containing a piston with a spring to urge the piston toward a normal end position, passages cross connecting the front end of each cylinder to the rear end of the other cylinder, and connections from said passages to the respective outlet pipes of the jet pipe relay, and said cross-connections preventing simultaneous operation of the valves.

2. An automatic control system, as set forth in

claim 1, in which the system is provided with an oil sump for the hydraulic fluid and an air bubbling device is associated with the oil sump and connected to create control impulses acting on the jet pipe relay in response to changes in level of the coupling fluid in the sump.

3. An automatic control system, as set forth in claim 1, wherein the servo-motors have piston rods projecting through oil baffles near one end of each cylinder to prevent friction and wherein an oil drain is connected to each cylinder beyond said baffles.
